ELECTRIC SHAVER

Melvin H. Boldt, Glenview, Ill., assignor to Schick
Electric Inc., a corporation of Delaware

Filed Oct. 23, 1963, Ser. No. 77,102

Term of patent 14 years

(Cl. D22—3)

FIG. 1 is a top plan view of an electric shaver, showing my new design;

FIG. 2 is a front elevational view thereof;

FIG. 3 is an elevational view of one side of the electric shaver;

FIG. 4 is an elevational view of the other side thereof and

The rear elevational view (not shown) is substantially the same as the front elevational view.

I claim:

The ornamental design for an electric shaver, substantially as shown and described.
